Primary Examiner — Rhea Shields(74) *Attorney, Agent, or Firm* — Taft, Stettinius & Hollister; J. Bruce Schelkopf(57) **CLAIM**

The ornamental design for a power distribution device, as shown and described.

DESCRIPTION

FIG. 1 is a front, left perspective view of a power distribution device showing our new design.

FIG. 2 is a front elevational view thereof.

FIG. 3 is a rear, right perspective view thereof.

FIG. 4 is a rear elevational view thereof.

FIG. 5 is a top plan view thereof.

FIG. 6 is a bottom plan view thereof.

FIG. 7 is a left side elevational view thereof; and,

FIG. 8 is a right side elevational view thereof.

In the drawings, the broken lines are for the purpose of illustrating environment only and form no part of the claimed design.

1 Claim, 8 Drawing Sheets(56)
